FLANGING MACHINE

Filed Nov. 22, 1929

INVENTOR
GEORGE F. SCHULENBURG.

BY *Arthur C Eckert*
ATTORNEY

UNITED STATES PATENT OFFICE

GEORGE F. SCHULENBURG, OF ST. LOUIS, MISSOURI

FLANGING MACHINE

Application filed November 22, 1929. Serial No. 408,946.

The object of my invention is to make a flanging machine.

A still further object is to make a machine for making flanges on perforations in metal plates.

A still further object is to make a machine for forming flanges on the peripheries of circular holes in the heads of metal barrels or drums. My machine may be equally well used in making flanges on holes of various shapes, but I have illustrated a device for making the flanges on circular openings. My machine does not concern itself with the cutting of the hole in the metal sheet or head. My device is illustrated when operating on the head of a metal barrel or drum. My machine dispenses with the use of rollers and is made of few and simple parts that lend themselves readily to multiple production. The process consists generally in punching or bending the sides of an existing hole in a metal plate for the purpose of producing an inwardly extending circular flange.

With these and other objects, my invention has relation to certain novel features of construction and arrangement of parts as will be hereinafter more fully described, pointed out in the claims and illustrated in the drawing in which

Fig. 1 is an elevation partly in section of my device showing the barrel or drum in position to have a flange formed on the circular hole in the upper head.

Fig. 2 is an end elevation of the machine shown in Fig. 1.

Fig. 3 is an enlarged sectional elevation of the flange forming elements of my device, showing a portion of the drum with the perforation therein before the flange is formed on the perforation.

Fig. 4 is a sectional elevation of the die holder and die forming a portion of the flange turning element showing it in the position that the portions of the die assume in placing them in position, as well as showing portions of the head in cross section.

Fig. 5 is an enlarged fragmental sectional elevation of a portion of the head after the flange is formed, together with a portion of the die and die holder showing the relative

positions immediately after the flange has been formed.

Fig. 6 is a plan view of the die showing its parts in position relative to each other and around its spindle.

Numeral 7 indicates the barrel support generally, having the base 8 and the side members 9 and 10. The side members 9 and 10 are secured together at the upper portion by means of the beams 11 and 12. Numeral 13 designates the barrel having the hole 14 formed in its head 15. On the top of the side member 10 is positioned the hanger 16. On the top of the side member 9 is positioned the hanger 17. Numeral 18 designates the drive shaft journaled in bearings in the hangers 16 and 17. Numerals 19 designate pulleys secured in selective sliding engagement on the drive shaft 18. Numeral 20 designates a belt in operative connection with one of the pulleys 19, and 21 designates a belt in operative connection with the other pulley 19. The belts 20 and 21 are in operative connection with the pulley on a power source, such as a motor or engine. The belt 20 is driven in the direction of the arrow shown adjacent it and the belt 21 is driven in the direction of the arrow shown adjacent it. This structure is supplied in order to be able to selectively rotate the drive shaft 18 in either a clockwise or an anti-clockwise direction. By having a sliding key in a keyway on the drive shaft 18, and corresponding slots in the pulleys 19, either pulley may be secured against rotation relative to the drive shaft 18. The pulley that is not secured to the drive shaft 18 at a particular time will be in rotating slipping engagement with the drive shaft 18. It is intended to describe conventional structure thus far. Any two-way clutch may be used in place of the structure described.

Numeral 22 designates a pinion keyed to the end of the drive shaft 18 protruding laterally beyond the hanger 17. Numeral 23 designates a shaft passing through the journal box 24 secured in the side member 9 in the position shown in Fig. 1. Numeral 25 designates a gear keyed to the shaft 23 external to the side member 9, so

that it will be in mesh with the pinion 22. On the inner end of the shaft 23 is keyed the beveled gear 26. Numeral 27 designates a vertical spindle to which is keyed the beveled gear 28, which is in mesh with the beveled gear 26. The end of the spindle 27, above the beveled gear 28, is in threaded engagement in the journal box 29. Numeral 30 designates a circular plate secured to the beam 11 by means of the screws 31. Numeral 32 designates an annular slot formed in the spindle 27 near its lower end. Numeral 33 designates a circular die formed of a plurality of segments, preferably 4, as shown 10 in Fig. 6. Numeral 34 designates a circular die holder having a central hole 35 formed therein. The circular die holder is secured to the spindle 27 by having the spindle 27 passing through the central hole 35 and by having the nut 36 secured by threaded engagement to the end of the spindle 27 below the circular die holder 34. The die 33 has the hole 37 formed therein and has the lower edges of the hole beveled upward. 15 The die 33 is formed with the circumferential projection 38 connected with the circumferential projection 39, which two projections are connected integrally by the horizontal portion 40. On the periphery of the circular die holder 34 is formed the annular projection 41. It will be seen that by this construction that the die 33 can be fitted into the circular die holder 34 as shown in the drawing, the die being of such thickness 20 that its end may project into the annular slot 32. The upper end of the annular projection 41 of the circular die holder supports the horizontal portion 40 of the die 33. The spindle 27 at its upper end is externally threaded and in mesh with threads in the journal box 29. It will be seen that when the drive shaft 18 is driven in one direction that the spindle 27 will be moved downwardly thereby moving the die 33 and the circular die holder 34 downwardly, and when the drive shaft 18 is driven in the opposite direction that the die 33 and the circular die holder 34 will be moved in the opposite direction vertically. 25 The operation of my device is as follows: The barrel 13 is positioned on the base 8 between the side members 9 and 10 centrally, as shown in Fig. 1. The spindle 27 is lowered by the application of power to the drive shaft 18 as previously described passing the circular die holder through the hole 14 in the head 15 immediately beneath the head 15. The segments of the die 33 must now be placed 30 manually in position in the circular die holder 34 and immediately beneath the head 15. It is in order to enable this positioning that the die is formed in segments rather than in a single piece. If it were formed in a single piece, it would not be physically possible to position it in the hole 14, which

hole, as previously described, is of lesser diameter than the diameter of the die 33 itself. This positioning is also facilitated by reason of the upturned lower edges of the hole 37 in the die 33. When the die 33 is in the proper position, as described, as well as having the upper face of the circumferential projection 39 in contact with the lower surface of the head 15, the movement of the spindle 27 upwardly is begun. This movement brings the peripheral edge of the circumferential plate 30 in contact with the edge of the hole 14. A continuation of this process bends over the peripheral edge of the hole 14 forming the flange 42, when the circumferential plate is in the position shown in Fig. 5. When the flange is formed, the rotative direction of the drive shaft 18 is reversed and the spindle 27 lowered thereby disengaging the die 33 and the circular die holder 34 from the head 15. When the die 33 is lowered sufficiently owing to its being in segments, the segments may be removed manually, the operation being the reverse of that performed in positioning the segments in position originally. After the die 33 is removed, by continuing the upward movement of the circular die holder 34, it may be raised above the head 15 and the barrel removed. 70 75 80 85 90 95 100 105 110 115 120 125 130

What I claim and mean to secure by Letters Patent is:

1. In a device of the character described, a spindle, means of moving said spindle longitudinally, a die holder secured to said spindle, a die positioned on said die holder, a circular plate, said plate and said die being so positioned relatively that the vertical movement of said spindle will bring said die and said circular plate in and out of frictional engagement. 100 105
2. In a device of the character described, a barrel support, a drive shaft operatively positioned on said support, a spindle secured in said support and operatively connected to said drive shaft, a die holder secured to the lower end of said spindle, a die composed of a plurality of segments positioned on said die holder and around said spindle and having the inner radial ends of the segments of said die projecting within an annular slot formed on said spindle and having the lower inner edges of the segments of said die beveled upwardly, a circular plate secured to said support around said spindle centrally relative to said die and of a diameter less than the operative diameter of said die. 110 115 120

In testimony whereof I affix my signature.
GEORGE F. SCHULENBURG.
